Primary Examiner — Brett Miller*Assistant Examiner* — Sara Michie Pottenger(74) *Attorney, Agent, or Firm* — Howard M. Cohn(57) **CLAIM**

The ornamental design for a garage with storage units, as shown and described.

DESCRIPTION

FIG. 1 is a perspective front view of a garage with storage units.

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines depict environment and form no part of the claimed design.
